FLUID PRESSURE ACTUATED PRESSING MACHINE

Joseph P. Daly, Cincinnati, Ohio, assignor to The Daly Manufacturing Company, Cincinnati, Ohio, a corporation of Ohio

Application February 13, 1929, Serial No. 339,673

18 Claims. (Cl. 68—9)

My invention relates to garment or ironing pressing machines operated by a fluid pressure motor such as a pneumatically operated piston or pistons within one or more cylinders.

5 In fluid pressure actuated presses such as clothing presses and laundry presses, such high pressure is attained that there is a constant problem to eliminate the chance that the operator or someone else working in the establishment where 10 the press is being used will have some part of his body pinched between the press jaws or head and buck. It has been proposed to employ a dual control for a pneumatically operated motor means, which control requires the use of both 15 hands for closing the press, thereby obviating the possibility that the operator will carelessly allow his hands to be pinched between the press jaws, but I find this safety feature does not entirely eliminate the danger of some other workman 20 carelessly allowing part of his body to be caught during the closing of the press.

It is the object of my invention to provide a system of levers which will be rendered inoperable and thus cannot effect final jaw compression if some foreign matter, other than the articles 25 to be pressed, should prevent the press from closing. Thus, if the operator of the press is proceeding with a pressing operation and some unauthorized person allows himself to be caught 30 between the pressing members, the lever and power transmission means will be rendered inoperable.

Another object is the incorporation in the lever system of a compound toggle link system, the 35 movement of the links of which are accelerated from open to closing position in which position the links act as a pressure lever. A further object is the provision of mechanism in which the lever formed by the toggle links transmits the 40 power for the compression stroke of the press.

I have as a further object the provision of a locking device which will permit the release of the fluid pressure from the motor while the jaw pressure is still on the work to be ironed, and 45 which preferably travels through a radius corresponding to the radius of travel of the parts actuated by the fluid pressure motor. It is also an object to provide a locking device for holding the pressing jaw members together which acts as 50 a stop to prevent overrunning of the actuating mechanism, which would lock the mechanism so that the springs or counter-weights will not open the press.

A further object is to produce a novel two-hand 55 control press wherein the operator holds both

hands on the two-hand control means 51—51 while the press is closing, thus insuring safety to the operator.

The above and other objects to which reference will be made in the ensuing disclosure I accomplish by the combination and arrangement of part of which I have shown a preferred modification.

Referring to the drawings:—

Figure 1 is a side elevation of an example of 10 the invention, with parts shown in section and with certain center lines shown to indicate the relative positions of the parts during their cycles of movement.

Figure 2 is an enlarged diagrammatic view, with 15 parts shown in section, of the fluid pressure motor and its two-hand control system detached from a press.

Figure 3 is a diagrammatic side elevation of the compound toggle link actuating mechanism in 20 open position, with certain center lines indicating the relative position of the parts during their movement.

Figure 4 is a diagrammatic side elevation of the compound toggle link mechanism in closed 25 position in which it acts as a pressure link or lever, certain center lines being also indicated to indicate the relative movement of the parts from that which they occupy in Figure 3.

The pressing machine consists of a base 1 30 from which upright supports 2 extend, on which the pressure table 3 is mounted. The pressure table 3 carries the buck 4 which, as indicated, is mounted on an upright support 5. In an upright frame member 6 a press lever 9 is pivotally mounted as indicated at 7 and carries a head 8 which is moved down into pressing engagement with the buck, and includes a rearwardly extending portion 9 through which power is transmitted to perform the pressing operation. Changes in the relative size and relation of the parts of the mechanism heretofore described may be made without departing from the principle of my invention, as I have merely illustrated what might be called a standard 40 type of clothing or laundry press, which I have selected because my fluid pressure actuating mechanism and the controls therefor are adapted for use with this type of press.

Referring now to Figure 2, it is my purpose 50 to provide a motor such as is indicated in sectional view. The motor is composed of a cylinder member having two cylindrical shells, an upper shell or cylinder 10 and a lower shell or cylinder 11, joined together by a casing or sleeve 55

11a in which the intake and outlet ports for the cylinders are provided. The upper cylinder has a cap 12 through which extends a piston or connecting rod 13 connected with the upper piston 14. The end of the piston rod is provided with some suitable mounting device such as the eye 15 which is attached to a boss 16 formed on the machine frame. Other devices which will also permit restricted pivotal movement of the pneumatic cylinder may also be provided.

The lower cylinder has a cap 17 through which the piston rod 18 extends, the piston rod being connected to the piston 19. The piston rod 15 has a boss 20 on its end which is pivotally connected to an arm 21 of a bell crank lever. The bell crank lever is journaled on a shaft 22 mounted in the machine frame. The short arm 23 of the bell crank extends upwardly and has a pair 20 of toggle links connected thereto. The lower toggle link 24 is pivotally connected to the arm 23 as indicated at 25. The knuckle of the toggle links is indicated at 26 and the upper toggle link 27 has preferably an adjustment wheel 28 25 which, through a right and left hand threaded bolt, extends from a boss 29 which is pivotally connected to the end of the arm 9.

The toggle links are provided with stops such as the aligned flat surfaced portions 30, 31 at 30 the knuckle which form a straight link or lever from the toggles when they are moved to a position beyond the center. Flattened surfaces 32, 33 are also formed to act as stops for the connection between the lower toggle and the short 35 arm of the bell crank.

In order to exert a spring pressure on the knuckle to accelerate the straightening of the toggles when the long arm of the bell crank is depressed, I have provided a connection, preferably resilient, which, in the modification illustrated, comprises a bell crank having a long arm 34 with a spring 35 which connects with the lower toggle just below the knuckle, and a short arm 36 which may also be connected with the long arm of the bell crank as by a spring 37. Preferably the spring 37 will be stronger than the spring 35 so that the initial downward movement of the long arm of the bell crank immediately accelerates the closing of the toggles.

It will also be noted that the mechanism, represented by the springs 35 and 37 and the bell crank 34, 36, comprises means which tend to keep the toggle links 23 and 24 in bent position or inoperative until the toggle links 24 and 27 have reached straightened position with the stops 30, 31 engaging each other. When the links 24 and 27 are prevented from further pivotal movement upon the pivot 26, the links 23 and 24 begin to straighten for final heavy pressure. There is then a double toggle action in that during the initial closing movement of the press, the toggle is represented by a long power link including links 23 and 24 as one link and link 27 as the other link. This is a fast closing press 60 toggle. In the final closing action, the toggle becomes a short high power link 23 and a long link including links 24 and 27 acting as a unit.

I may further provide means for causing the press to open up when the locking control is relieved which may be in the form of a spring 38 connecting the machine frame and the long arm of the bell crank.

The manual controls for the movement of the pressure motor is preferably in the form of a two button control with the buttons sufficiently far

apart as to require the use of both hands to operate them. Thus I have shown the button control at the right in Figure 2 composed of a casting 39 within which is a rocker arm 40 pulled up into the position indicated by a spring 41. The rocker actuates the valve mechanism for opening and closing the port for admitting compressed fluid to the upper cylinder and for exhausting the same. The valve mechanism consists of a cylindrical valve casing 42 having an inlet port 43 supplied with compressed fluid from the supply pipe 43a. The port 44 intermediate the ends of the valve cylinder 42 admits compressed fluid to the pipe 45 leading to the port in the upper motor cylinder. The exhaust port in 10 the valve cylinder is indicated at 46. Valve heads 47 and 48 mounted on a stem 49 with the elevation of the rocker 40 admit air to the port 44 and pipe 45 and close the exhaust port 46. A spring 50 bearing against the valve disc 47 causes the admission port to be closed and the exhaust opened when the operator removes his finger or hand from the push button 51 which engages the raised end of the rocker 40.

The control for the lower cylinder 11 is exactly 25 the same as that for the upper, similar numbers being applied to the parts for the control valves for the lower cylinder.

In order to economize in the time required to exhaust the air or compressed fluid from the motor cylinders, I have provided a locking device which the operator may actuate by a control either from the machine in use or from one arranged next to it. Compressed fluid is supplied to a cylinder 52 from the supply pipe 43a through 30 a pipe 53. Within the cylinder 52 there is a piston 54 and its rod 60 which extends through the end 56 of the cylinder. A valve 57 controls the passage of compressed fluid from the supply line 53 to the cylinder 52. A link 58 is connected 35 to an arm 59 which controls the valve. The piston rod 60 has its outer end anchored to a hub 55 integral with a fork 61 which has a pivotal connection with a rocker lever 62 which is connected to the link 58. The rocker has an enlarged boss 45 63 through which a pivot pin is extended connecting it to an arm 64 pivoted on the same shaft 22 as the bell crank lever, so that the locking slot 65 on the rocker 62 will move through the same 50 arc as the pin 66 carried by the long arm 21 of the bell crank.

When both spaced manual controls 51 for the two motor means 10 and 11 are operated the pistons 14 and 19 will travel on their out strokes forcing the pin 66 to interlock with the slot 65 and pull out on the piston. This same movement causes the locking device to move clockwise and lock the bell crank and toggle links in pressing position 54. Also coincidently the valve 57 is opened which causes the piston 54 to advance to 60 the end of its stroke where it will remain under compression and where its contact with the end of the cylinder prevents the mechanical parts from over-running.

To release the locking control an enlarged port 65 and a pipe 67 extend to an exhaust valve 68 having a spring pressed valve head 69 which may be opened by means of the handle 70. The release valve 68 for the locking control may thus be located in any desired point of remote control 70 so that an operator may leave the machine after releasing both manual controls 51 for the pressure motor and then busy himself at another machine, and then, before returning to the original machine, the release button for the original ma- 75

chine may be operated so that, by the time he returns, the press will be opened up. Thus some economy of time is made possible.

The two cylinders 10 and 11 are placed end to end or in axial alignment with the upper piston rod 13 pivoted on the press frame and the lower piston rod pivotally connected to any suitable lever means 21 adapted to actuate the upper press jaw or head 8 up and down in relation to the buck 10. Hence the double cylinder means 10-11 is suspended between the press frame and head operating leverage or means 21-9 so that the cylinder means floats or is mobile on its two pistons 14 and 19.

An air pressure line 45 and manually operable valve control means 51 is provided for each separate cylinder 10 and 11 which necessitates the use of both hands of the operator who must depress both buttons to send a flow of air from the pressure supply line 43a through both feed lines 45 to the two cylinders 10 and 11 to drive both cylinders downwardly along both pistons 14 and 19 and to force the lower piston 19 outwardly from the cylinder 11. Motive fluid or air pressure transmitted to one cylinder alone will not fully close the press head inasmuch as the length of the stroke of only one cylinder 10 or 11 is insufficient to close the press head and produce pressure. The total length of the piston or cylinder strokes is sufficient to fully close the head onto the buck and produce jaw compression.

While I have disclosed only a preferred modification of my invention, it will be readily apparent that changes in the mechanical construction 35 may be made without departing from the inventive principle involved.

Having thus described my invention, what I claim as new and desire to secure by Letters Patent, is:—

1. In combination with a pressing machine having a relatively fixed pressing member and a pressing member movable into pressing engagement with the fixed member, a fluid pressure motor having mechanical connections with the movable member for moving the pressing member into pressing engagement with the fixed member comprising a cylinder, subdivided intermediate its ends into plural cylinders, a piston in each of said cylinders, and controls, one for each of said cylinders, for compressed fluid introduced into each of said subdivided cylinders, said controls being spaced apart so as to require the use of both the hands of an operator to manipulate same.

2. In combination with a pressing machine having a frame and relatively fixed pressing member and a pressing member movable into pressing engagement with the fixed member, a fluid pressure motor for moving the movable pressing member into pressing engagement with the fixed member comprising a cylinder subdivided intermediate its ends into plural cylinders, a piston in each cylinder, a rod for each piston and controls one for each cylinder for admitting compressed fluid into each of said subdivided cylinders, said controls being spaced apart so as to require the use of both the hands of an operator to manipulate same, operating connections between one piston rod and the movable pressing member, and the other piston rod being attached to the press frame.

3. In combination with a pressing machine having a relatively fixed pressing member and a pressing member movable into pressing engagement with the fixed member, a fluid pressure

motor means for moving the movable pressing member into pressing engagement with the fixed member comprising a cylinder subdivided intermediate its ends into plural cylinders, a piston and connecting rod in each of said cylinders, and spaced two-hand controls one for each cylinder for admitting compressed fluid into each of said subdivided cylinders so as to require the use of both the hands of an operator to manipulate same, mechanism connecting one of said pistons and the movable presser member, and means for locking said mechanism in pressing position.

4. In combination with a pressing machine having a relatively fixed pressing member and a pressing member movable into pressing engagement with the fixed member, a fluid pressure motor for moving the movable pressing member into pressing engagement with the fixed member comprising a cylinder subdivided intermediate its ends into plural cylinders, multiple pistons in said cylinders, and spaced two-hand controls one for each cylinder for admitting compressed fluid into each of said cylinders so as to require the use of both the hands of an operator to manipulate same, mechanism connecting one of said pistons to the movable pressing member, and fluid pressure controlled means for locking said mechanism in pressing position.

5. In combination with a pressing machine having a relatively fixed pressing member and a pressing member movable into pressing engagement with the fixed member, a fluid pressure motor for moving the members into pressing engagement, and mechanism connecting said fluid pressure motor and said movable member comprising a bell crank and toggle links, the end of one of which is connected with said movable member, and the end of the other of which is connected with an arm of said bell crank, said toggle links being equipped with stops to limit their movement when straightened out, and means connecting the knuckle of said toggle links and said bell crank whereby the movement of the bell crank will accelerate the closing of said toggle links.

6. In combination with a pressing machine having a relatively fixed pressing member and a pressing member movable into pressing engagement with the fixed member, a fluid pressure motor including two cylinders and a manual control for each cylinder for moving the members into pressing engagement, and mechanism connecting said fluid pressure motor and said movable member comprising a bell crank and toggle links, the end of one of which is connected with said movable member, and the end of the other of which is connected with an arm of said bell crank, and means interconnected between the motor means and toggles for accelerating the closing of said toggles.

7. In a pressing machine having a relatively fixed buck and having a presser head movable into pressing engagement with said buck, a fluid pressure motor including two cylinders and a manual control for each cylinder, and mechanical connections between said motor and presser head, said mechanical connections comprising toggle links constructed and arranged to assume a straightened position for transmitting a power stroke only when the presser head is substantially closed on said buck, said mechanical connections including a bell crank to which said toggle links are connected, and means for ac-

- celerating the closing of said toggle links comprising resilient means interconnected between the bell crank and toggle and tensioned with the movement of said bell crank.
5. 8. A pressing machine having a movable head and a buck and a double cylindered, double pistonned fluid pressure motor for actuating same, plural controls one for each of said pistons of said motor, and a mechanical safety device for 5 preventing the operation of said press when said head is blocked from free movement toward said buck.
10. 9. A garment or ironing press comprising a frame and coacting press jaws, fluid pressure 15 motor cylinders disposed in axial alignment, a piston and connecting rod in one cylinder and operatively connected with one press jaw, a piston and connecting rod in another cylinder and attached to the press frame, the cylinders being 20 operatively connected together whereby one motor cylinder and piston is moved bodily, an independent fluid pressure line having a manual control valve connected to each cylinder to admit pressure thereinto against each piston, and the 25 control valves being spaced apart to provide a safety multiple hand control means for the motor cylinders.
10. 10. A garment or ironing press comprising a frame and coacting press jaws, fluid pressure 30 motor cylinders disposed in axial alignment, a piston and connecting rod in one cylinder and operatively connected with one press jaw, a piston and connecting rod in another cylinder and attached to the press frame, the cylinders being 35 joined together and movably mounted between the press frame and the press jaw and hence adapted to reciprocate in relation to the pistons, an independent fluid pressure line having a manual control valve connected to each cylinder to admit 40 pressure thereinto against each piston, and the control valves being spaced apart to provide a safety multiple hand control means for the motor cylinders.
45. 11. A pressing machine comprising a frame and coacting press jaws, a pair of pistons and piston rods, the outer end of one piston rod being attached to frame and the outer end of the other piston rod being operatively connected with one of the press jaws, a cylinder mounted on each 50 piston and free to reciprocate in relation to the piston rods fixed to the frame, a flexible pressure feed line including a manually controlled valve in communication with each cylinder, the valves being spaced apart on the press to provide a two-hand control, and the two cylinders being 55 connected together so that the piston rod, which is operatively connected with the press jaw, and its piston and cylinder are moved bodily.
60. 12. A pressing machine comprising coacting press jaws, motor means, operating connections interconnected between the motor and a press jaw including an arm pivoted on a frame pivot, a locking device motor means, and a locking device actuated by the motor means and engaging 65 the arm to grip and hold the first named motor means in operated position to hold the press closed.
70. 13. In combination in an ironing machine, an ironing buck, an ironing head, a cylinder structure having a primary chamber and a secondary chamber, a piston in said primary chamber connected with said ironing head, a piston in said secondary chamber anchored to a rigid support, conduit means for fluid under pressure, a valve 75 for controlling the flow of fluid from said conduit means to said primary cylinder chamber to cause movement of the piston therein and primary movement of the head relative to the buck, and a second valve for controlling the flow of fluid from said conduit means into said secondary chamber whereby said cylinder structure will be bodily moved relative to said anchored piston to cause final movement of said head relative to said buck.
14. In a pressing machine having a relatively fixed buck and a presser head movable into pressing engagement with said buck, a fluid pressure motor, and mechanical connections between said motor and said presser head including a three link toggle means having a toggle knee at 15 the connection between each link, a stop means at each toggle knee, and means resiliently retaining the first two toggle links against relative pivotal movement with the stop means in engagement during the initial closing of the press and 20 permitting relative movement during the final closing of the press.
15. A press comprising a head and operating mechanism including a compound toggle having three links pivoted end to end and means for 25 constraining the toggle to break about one of said pivots for a portion of the movement of the head and about another of its pivots for the remainder of its movement.
16. A garment or ironing press comprising a 30 press frame, cooperating press jaws including a buck and a head, a pivoted press lever carrying the head, a compound toggle connected to the press lever including an upper link, a middle link and a lower link which links are pivoted together 35 end to end, the lower link being pivoted in the frame, said compound toggle comprising an upper toggle having the upper link as a short work arm and the middle and lower links combined as a long operating arm and a lower toggle having the 40 upper and middle links as a long work arm and the lower link as a short operating arm; resilient means to retain the lower toggle inoperative while the upper toggle is closing, means to lock the upper toggle in dead center position, and 45 means to actuate the toggles.
17. A garment or ironing press comprising a press frame, cooperating press jaws including a buck and a head, a pivoted press lever carrying the head, a compound toggle connected to the 50 press lever including an upper link pivoted at one end to the press lever and at the other end to the end of a middle link, a middle link, and a lower link pivoted in the frame and having its end pivoted to the lower end of the middle link, 55 said compound toggle comprising an upper toggle formed by the upper link as a short work arm and the middle and lower links together as a long operating arm and a lower toggle formed by the upper and middle links as a long work arm 60 and the lower link as a short operating arm, locking means to retain the upper toggle in dead center position, stop means to prevent the lower toggle from opening more than a predetermined extent, spring means retaining the lower and 65 middle links in open position against the stop means, and actuating means to swing the lower link to close the compound toggle and operate the head.
18. A garment or ironing press comprising a 70 press frame, cooperating press jaws including a buck and a head, a pivoted press lever carrying the head, a compound toggle connected to the press lever including an upper link pivoted at one end to the press lever and at the other end 75

to the end of a middle link, a middle link, and a lower link pivoted in the frame and having its end pivoted to the lower end of the middle link, said compound toggle comprising an upper toggle formed by the upper link as a short work arm and the middle and lower links together as a long operating arm and a lower toggle formed by the upper and middle links as a long work arm and the lower link as a short operating arm, locking

means to retain the upper toggle in dead center position, stop means to prevent the lower toggle from opening more than a predetermined extent, spring means attached at one end to the middle link to normally retain the middle and lower links in open position, and actuating means to swing the lower link to close the compound toggle and operate the head.

JOSEPH P. DALY.
